UNITED STATES PATENT OFFICE.

FRANK A. GURNEY, OF CHICAGO, ILLINOIS.

WIRE-SPlicer.

SPECIFICATION forming part of Letters Patent No. 269,498, dated December 19, 1882.

Application filed May 18, 1882. (No model.)

To all whom it may concern:

Be it known that I, FRANK A. GURNEY, of Chicago, in the county of Cook and State of Illinois, have invented certain new and useful 5 Improvements in Wire-Splacers, of which the following, in connection with the accompanying drawings, is a specification.

In the drawings, Figure 1 is a perspective view of a wire-splicer embodying my invention. Fig. 2 is a like representation, showing the manner in which the splicer may be applied to use; and Figs. 3 and 4 represent modifications in construction.

Like letters of reference indicate like parts. 15 This tool I make of metal.

A is the head of the tool, and B is the handle.

C is a deep notch in the head A. This notch extends from the end of the tool nearly to the 20 handle, as shown, and is sufficiently wide to receive the wire or wires to be spliced.

D is a deep groove, extending across the head A and intersecting the notch C.

a a are lips projecting part way over the 25 groove D. The space between the lips a a is sufficient to admit of the reception of the wire or wires to be spliced. I deem it preferable to cut away the corners at the intersection of the notch C and groove D, as indicated at b b.

30 In order to use the device for the purpose for which it is intended, I proceed as follows: For example, suppose that a fence-wire, consisting of two strands twisted together, is to be spliced, and that E represents one part of such a wire and E' the other part. To splice these parts I lap the ends to be united and grasp the lapped portions firmly with a pair of tongs or other suitable clamping device or tool held in one hand. I then take the splicer 40 in the other hand and place this tool astride or across the lapped portions, which will then lie in or pass through the lower or inner end of the notch C. I then bend the free ends of the two strands to be wound upon the other 45 two, so that the parts to be wound will lie in opposite directions in the groove D. I then

turn the splicer around upon the lapped portions of the wire, which serve as an axis or bearing for the splicer. The ends lying in the groove D will be caught underneath the lips 50 a a, and so be retained in the groove until the operation of splicing those ends is completed. It will be perceived that the projecting ends of the wires will thus be wound tightly, firmly, and smoothly, and spirally side by side upon 55 the horizontal strands. The splicer may then be withdrawn from the wire and replaced in such manner that the other ends of the strands may likewise be twisted upon the horizontal strands, thus completing the operation of splicing and making a neat and very strong connection or splice. The ends of the strands to be wound upon their fellows may be bent and arranged in the groove D after the splicer is applied. 60

I have now described the manner in which a double wire may be spliced; but it is obvious that a single wire may also be spliced by a similar operation, in which case only one-half the groove D need be utilized. 65

This splicer is simple in its construction and operation, is strong, durable, inexpensive, and light, and is not cumbersome or bulky.

The groove D forms shoulders, which, however, need not be continuous; and in Figs. 3 70 and 4 I have shown shoulders or lugs which lie one on each side of the notch C, and one a little way forward of the other.

Having thus described my invention, what I 75 claim as new, and desire to secure by Letters Patent, is—

A wire-splicer consisting of the head A, provided with a handle, the said head having therein the notch C, admitting of the splicer being placed astride the wire or wires to be 80 spliced, and the recessed transverse groove D, substantially as and for the purpose specified.

FRANK A. GURNEY.
